LOUIS STEINBERGER, OF NEW YORK, N. Y.

SAFETY STRAIN DISK INSULATOR.

1,206,159.

Specification of Letters Patent. Patented Nov. 28, 1916.

Application filed July 25, 1912. Serial No. 711,467.

To all whom it may concern:

Be it known that I, LOUIS STEINBERGER, residing at Brooklyn, in the county of Kings, city and State of New York, have 5 invented certain new and useful Improvements in Safety Strain Disk Insulators, of which the following is a specification.

This invention relates to an insulator of the safety strain type adapted for use in 10 general electric work, and more particularly for service where high voltages are present, and in instances where the insulator is subjected to a great mechanical strain, and it comprises a pair of metallic 15 disks arranged substantially concentric with each other and spaced apart by an insulating material, and said disks having strain members attached thereto in such manner as to tend to force said disks toward each other 20 against the intervening insulating material, in resisting the mechanical stresses to which the insulator is subjected.

Among the several objects of the invention, are:

25 I. To provide the metallic disks each with an elongated opening through the material thereof extending from a point adjacent one marginal edge of the disk to a corresponding point at the relatively opposite marginal 30 edge of the disk, and to form said opening of a reduced width intermediate its length so as to leave relatively heavy portions of the material of the disk intact for the attachment of the strain members, and to arrange 35 the two disks in the finished structure, so that the elongated openings stand in right-angular relation in order that the two legs of the U-shaped strain member, which legs are attached to the relatively heavy portion 40 of one disk, may extend through the relatively large portions of the opening of the other disk and be insulated therefrom by the main body of insulating material, and so that the peripheral edge portion of each 45 disk is maintained intact and continuous to rigidly connect the relatively heavy portions at opposite sides of the openings in the disk and serve effectually to oppose the strains applied to the disks by the strain members.

50 II. To form the disks as above, with relatively heavy portions, at opposite sides of an elongated opening, and to fix the strain members rigidly to the disks, before applying the fictile body of insulating material, 55 by having the legs of said strain members projected through suitable apertures formed

in the relatively heavy portions and retained against relative longitudinal movement by shoulders at one side of the disk drawn into close clamping relation with said 60 disk by suitable adjustable means at the opposite side of the disk.

Other objects and aims of the invention, more or less broad than those stated above, will be in part obvious and in part specifically referred to in the course of the following description of the elements, combinations, arrangements of parts and applications of principles constituting the invention; and the scope of protection contemplated 70 will be indicated in the appended claim.

In the accompanying drawings in which I have illustrated a merely preferred form of embodiment of the invention, and which are 75 to be taken as a part of this specification, Figure 1 is a longitudinal, central, sectional view, partly in elevation, through an insulator constructed in accordance with this invention; said section being taken substantially on the plane of line 1—1 of Fig. 2; Fig. 2 is a transverse, sectional view taken substantially on the plane of line 2—2 of Fig. 1, parts being shown in full lines; Fig. 3 is a detail, perspective view of one of the 85 disks; and Fig. 4 is a detail, perspective view of one of the strain members.

In insulators of this class, as heretofore constructed, the strain members have usually had no rigid connection with the metallic 90 disks such as would prevent the disks from having movement relatively to the strain members until after the parts are assembled in the finished structure, and I have observed that this condition has led to considerable inaccuracy and consequent waste and expense especially in the assembling of the device. It has been very difficult, if not practically impossible, to maintain the disks, with uniform accuracy, in their proper relation to the strain members to which they are directly connected, and to maintain said disks and strain members in proper relative positions while the parts are being molded within the fictile insulating material which 105 serves to bind them together. Ofttimes, efforts to maintain the disks in proper relation to the strain members result in a non-parallel relation of the opposing surfaces of the disks, and, as often, one leg, or portion 110 of the strain member, may be brought into physical contact with the disk and sustain

the parts inadvertently against further movement, while the other leg of the same strain member is actually spaced away from the disk. Thus, when the enveloping body material is molded about the metallic parts, the spaced portion of the strain member remains spaced until the device is subjected to a considerable strain, whereupon it gives way and fractures or otherwise destroys the structure.

I have provided herein a simple and efficient means whereby the disk and the strain members may be readily connected together, and have so shaped the disks that they may be formed with apertures adapted to receive the strain members without detracting from the effective strength of the disks in resisting strains imparted thereto from the strain members, the connections being rigid so as to effectually prevent bending of the disk under excessive strains.

Referring to the drawings, 1 indicates the strain members, which are of U-shape, having the opposite legs 2 and 3 preferably connected intermediate their length by a reinforcing spacing bridge 4, and having their end portions threaded to receive nuts 5, and having annular shoulders 6 formed thereon at points spaced from the extreme ends thereof. Each of the strain members is preferably identical in size and shape. The disks, as 7, are also preferably identical in size and shape, and each is formed with an opening 8 extending entirely through the material thereof and from a point adjacent the marginal edge at one side of the disk to a corresponding point at the opposite side of the disk. The opposite end portions of the opening are preferably rounded so that the maximum width of the opening is at a point spaced somewhat from its opposite ends, and the intermediate portion of the opening is of a somewhat reduced width so as to leave considerable portions 9 of the disk not cut away. The portions 9 are formed with apertures 10 spaced from the walls of the reduced portion of the opening 8, and adapted to receive those portions of the strain members between the shoulders 6 and the extreme ends of the legs of the strain members.

In assembling the parts, the end portions of the legs of the strain members are inserted in the apertures 10 so that the shoulders 6 engage the surface of the disk. Countersinks 11 are provided for partly receiving the shoulders 6, and thus avoiding unnecessary sharp corners. The nuts 5 are then placed upon the projecting ends of the legs and serve as adjustable clamping members for forcing the shoulders 6 into close clamping relation with the disks, and thus holding the disks rigid upon the ends of the strain members. Obviously, in assembling the opposite strain members, with their disks in

proper relative positions to each other, prior to the application of the insulating body material 12, one of the disks may be rigidly fixed upon its strain member as above described, after which the legs of the other strain member may be inserted through the opening 8 in the first disk, the second disk moved to position with its opening 8 telescoping over the loop end of the first strain member, and inserting the threaded ends of the second strain member through the apertures 10 of the second disk, and placing the clamping nuts in position. The opposite clamping members are then held in spaced relation and so that the opposite legs of the one extend through the opening 8 of the other disk in such manner as to be spaced substantially concentrically from the walls of the ends of said opening. The enveloping body of insulating material is then molded about the parts in any desirable shape, but preferably in that shown in the drawings, which, it will be noted, comprises a relatively thick disk 12 having its edge formed with annular corrugations as 13 for increasing the surface distance around said body material from one strain member to the other.

The connections between the legs of the strain members and the disks are designed to be absolutely rigid in practice so as to lend the strength of the legs in preventing tendency of the two halves of the disk to bend in the vicinity of the relatively thin connecting portions at opposite ends of the openings 8. It is thus made possible to form these connecting portions quite thin and weak so as to give a maximum size to the opening 8 for enabling a comparatively greater bulk of insulating material between the strain members passing through the opening 8 and the walls of said opening than would be possible were the connecting portions required to be thicker and stronger. Pull of the strain members is principally resisted by portions of the disks lying at the side of the point of connection of the strain members with the disks away from the openings 8 so that there is obviously a tendency for the halves of the disk to bend about an axis parallel with the length of the opening 8 extending through the point of connection between the disks and the strain members which tendency would be resisted only by the thin portions connecting the halves of the disks at the ends of the opening were it not for the absolutely rigid connection provided between the strain members and the disks.

As many changes could be made in this construction without departing from the scope of the following claim, it is intended that all matter contained in the above description or shown in the accompanying drawing shall be interpreted as illustrative only and not in a limiting sense.

Having thus described my invention, what I claim as new and desire to secure by Letters Patent, is:

In a strain insulator, a disk shaped member having an opening therethrough, said opening being of a length so as to leave a comparatively small amount of the material of said member between the opposite ends of the opening and the outer marginal edge 10 of said member, and being of a width so as to leave a comparatively great amount of material of said member between the opposite sides of the opening and the outer marginal edge of said member, the relatively 15 great amount of material at opposite sides of said opening being each formed with an aperture therethrough, a U-shaped strain member having its legs extended through and beyond said apertures, shoulders formed 20 upon the legs of said U-shaped strain member engaging one surface of said disk shaped member, nuts carried by the projecting portions of said legs and engaging the opposite surfaces of said disk-shaped member to clamp said disk-shaped member rigidly 25 against said shoulders, and the aperture at one side of the opening in said disk shaped member being arranged so that a line drawn parallel to the central longitudinal axis of the opening in said disk shaped member and 30 intersecting the central axis of said aperture will define surface extents at one side of the longitudinal central axis of the opening in said disk shaped member of substantially equal proportion at opposite sides of 35 said line.

In testimony whereof, I affix my signature in the presence of two witnesses.

LOUIS STEINBERGER.
